[57] **CLAIM**

The ornamental design for a cartridge for sensitive photographic films, as shown and described.

DESCRIPTION

FIG. 1 is a top and left-front perspective view of a cartridge for sensitive photographic films showing my new design;

FIG. 2 is a right side elevational view thereof;

FIG. 3 is a rear elevational view thereof;

FIG. 4 is a top plan view thereof, the bottom plan view being substantially a mirror image thereto.
